Inventor:

L. J. Mueller
By his attorney,
Philip T. Dodge

UNITED STATES PATENT OFFICE.

LOUIS J. MUELLER, OF MILWAUKEE, WISCONSIN.

SHEET-METAL PIPE.

SPECIFICATION forming part of Letters Patent No. 279,494, dated June 12, 1883.

Application filed April 4, 1883. (No model.)

To all whom it may concern:

Be it known that I, LOUIS J. MUELLER, of Milwaukee, in the county of Milwaukee and State of Wisconsin, have invented certain Improvements in Sheet-Metal Pipes, of which the following is a specification.

The particular aim of my invention is to produce a pipe the blank for which may be readily shipped in a compact form and the pipe completed therefrom by the purchaser without the employment of tools or mechanical appliances.

To this end it consists of a blank formed by incising and opening the edges of a metal sheet in the manner hereinafter explained, and in the pipe-sections formed therefrom.

Referring to the accompanying drawings, Figure 1 represents a perspective view of a completed pipe-section constructed on my plan. Fig. 2 is a face view of the incised sheet from which the blank is formed. Fig. 3 is a perspective view of the completed blank. Figs. 4 and 5 are cross-sections of the pipe on the lines $x x$, $y y$, Fig. 1, respectively. Fig. 6 is a face view illustrating a modified form of the blank.

In proceeding to construct my blank I provide a flat metal sheet, of rectangular form, of such dimensions as the character of the pipe may require.

In one edge of the sheet I form, near each end, two incisions, $a a$, at right angles, or substantially so, to the longitudinal edge of the sheet. In the opposite edge of the sheet I form, at right angles to said edge, or substantially so, two incisions, $d d$. That portion of the edge lying between the incisions $d d$, I bend or fold first backward upon the inner face of the sheet, and then forward again, in the peculiar manner represented in Figs. 3 and 4, thus forming along the edge of the sheet an open lip or a groove to receive the opposite edge of the sheet, as hereinafter explained.

It will be observed that the folding back of the edge e leaves two projecting portions at the ends of the sheet, as shown in Fig. 3. Through each of these projecting portions I

form an incision, c , in line transversely of the sheet, with the corresponding tongue, b , on the opposite edge.

The blank formed as above presents the appearance represented in Fig. 3, and may be placed in the market either in this condition or after being rolled into a substantially cylindrical form, with its edges still disconnected.

In forming the pipe from the blank thus constructed the blank is curled or bent longitudinally into a cylindrical, oval, or polygonal form in cross-section, as may be required, and that portion of the edge which lies between the tongues b is inserted within the grooved lip e on the opposite edge, as plainly represented in Figs. 1 and 4. At the same time that this operation is effected the tongues b are inserted through the openings or incisions c , preferably from the inside outward. The edges being now forced closely together, the projecting ends of the tongues or lips b are folded backward upon the outer surface, as represented in Figs. 1 and 5, thus locking the edges firmly together and completing the pipe.

While it is preferred to construct the tongues b upon the opposite edge of the sheet from the lip e , they may be in special cases placed upon the same edge, as represented in Fig. 6. Under ordinary circumstances I prefer to construct the tongues b and incisions c in the form represented; but they may be modified in form in various ways, which will readily suggest themselves to the skilled mechanician, without essentially changing their mode of action or departing from the limits of my invention.

The ends may be beaded or crimped, as usual.

Having thus described my invention, what I claim is—

1. The blank for a pipe, consisting of the rectangular metal sheet having in one edge transverse incision a , and in the opposite edge longitudinal incisions c and transverse incisions d , in substantially the positions set forth.

2. The finished blank for sheet-metal pipe,

consisting of a rectangular sheet provided with the open lip along one edge, and with the fastening-tongues and incisions to receive said tongues in opposite edges.

5 3. The improved sheet-metal pipe consisting of a metal sheet having one edge folded over the other in the manner described and

shown, and secured by tongues formed on one edge and seated in incisions in the opposite edge, as shown.

LOUIS JOHN MUELLER.
